UNITED STATES PATENT OFFICE.

JOHN B. DADE, OF FRANKFORT, NEW YORK.

WISE.

1,020,192.

Specification of Letters Patent. Patented Mar. 12, 1912.

Application filed April 22, 1911. Serial No. 622,706.

To all whom it may concern:

Be it known that I, JOHN B. DADE, a citizen of the United States, residing at Frankfort, in the county of Herkimer and State of New York, have invented certain new and useful Improvements in Vises, of which the following is a specification, reference being had therein to the accompanying drawing.

My invention relates to a vise and I declare the following to be a full, clear, concise and exact description thereof sufficient to enable any one skilled in the art to which it appertains to make and use the same, reference being had to the accompanying drawings in which like reference characters refer to like parts throughout the specification.

The object of the invention is to provide a vise that will be efficient in operation and of simple construction whereby the same may be cheaply manufactured.

The salient features of the device embody a jaw adjustably disposed relative to a slidingly mounted counter jaw which is actuated by the intermediate movement of an eccentric or cam controlled by a lever handle adapted to be retained in any position in its arc of movement by friction means.

Other features will appear from the drawings, in which:

Figure 1 is a side elevation of the device partially in section; Fig. 2 is a plan of the vise; Fig. 3 is a transverse section taken on the line 3—3 of Fig. 1; Fig. 4 is a transverse section taken on the line 4—4 of Fig. 1; Fig. 5 is an end elevation, somewhat diminished in size; Fig. 6 is a perspective view, enlarged, of a bolt employed on the device; Fig. 7 is a perspective of a plate, showing more particularly certain shoulders; Fig. 8 is a detail perspective of certain disks; Fig. 9 is a detail perspective of a sleeve; and Fig. 10 is a plan of the detail shown in Fig. 7; Fig. 11 is a plan view from beneath of Fig. 8, made to the scale of Fig. 1.

Referring more particularly to the drawings, the body of the device is preferably constructed from a metallic casting 1, having base or platform 2, laterally recessed, as at 3—3 etc. for the suitable mounting of the device upon any proper standard.

Upon opposite longitudinal sides of body 1, there are flanges 4—4 adapted to slidingly support jaws 5 and 6 having hardened faces 7 and 8 respectively, held to said jaws 5 and 6 by bolts 9, whose heads 10 are countersunk in the adjacent portion of said jaws 5 and

6. Faces 7 and 8 may be replaced by new ones whenever same become worn or destroyed by use of the device. Jaw 5 is adjustably held relatively to jaw 6 by pivotally mounted rack 11 having depending member 12, recessed at 13 for the vertically adjustable reception of the adjacent end of rack 11 upon stud or bolt 14 whose head 15 is counter sunk and remote end threaded at 16 whereby to be mounted in a correspondingly threaded bore in body 1. Said depending member 12 of rack 11 is elevated or lowered within the limits defined by recess 13 by means of set screw 17 mounted in the lower central part of member 12. The remote portion of rack 11 has a depending member 18 recessed transversely at 19 for the reception of one end of lever 20 pivotally mounted to said member 18 by bolt or screw 21. Said lever 20 is fulcrumed upon bolt 22 supported by lugs 23—23, integral with body 1. Bracket 11 is held in elevated position whereby its teeth 24 will be normally in mesh with teeth 25 upon the under surface of jaw 5, by coiled spring 26 mounted in recess 27 of the casting or body 1. In order to lower said teeth 24 of rack 11 so as to be out of mesh with teeth 25 of jaw 5, it is only necessary to pull upward upon the outer end of lever handle 20, which lever will cause rack 11 to swing downward upon bolt 14 as a fulcrum. Said pivotally supported end is vertically adjustable by the screwing or unscrewing of set screw 17.

Obviously, from the foregoing description, jaw 5 may be moved relatively to jaw 6 whereby to adapt the vise to articles of different dimensions.

Jaw 5 is confined to sliding movement along flanges 4—4 by cleats 28—28 secured to said jaw 5 by bolts or other suitable means 29—29 and adapted to project under the lower surfaces 30—30 of flanges 4—4.

Jaw 6 is similarly confined to flanges 4—4 by cleats 31—31 held to said jaw 6 by bolts 32—32 and is slidingly actuated to approach or recede from jaw 5 whereby to hold or release an object between jaws 5 and 6 by an eccentric mechanism now to be described.

Integral or otherwise connected with jaw 6 are two bearing brackets 33—33 between which there is pivotally mounted by pin or bolt 34, end 35 of metallic strap 36. The remote end 37 of said strap 36 embraces disk 38 having eccentrically disposed underneath the same and preferably integral therewith

a disk 39 which is shouldered at 40 and 41 to correspond with shoulders 42 and 43 of rectangular plate 44, slidingly mounted in ways or grooves 45—45 of body 1.

5 Above disk 38 or on the reverse side from that on which disk 39 is disposed is a hub or sleeve 53 concentric with disk 39 but eccentric with disk 38 with which it may be integral.

10 Plate 44, and disks 39, 38, and hub or sleeve 53 are held in assembled position, whereby disk 38 is eccentric to disks 39 and hub or sleeve 53 by wrist-pin 49 having rectangular shaped head 50 projecting on 15 either side under shoulders 51—51 formed in body 1, and slidingly mounted in recess 52 provided in casting or body 1. Said stationary adjustable plate 44 is held at any location along ways or grooves 45—45 by 20 means of collar 46 assembled upon wrist-pin 49 and bearing partially against shoulder 55 thereof and also against plate 44 when the parts are assembled. Said collar 46 bears against stationary adjustable washer 47 held 25 rigidly in vertical location by nut 48 screw-mounted upon wrist-pin 49.

The central portion of body 1 is recessed at 56.

The operation of the device is effected in 30 the following manner, namely: Nut 48 is tightened upon wrist-pin 49 to force sleeve 46 upon plate 44 and head 50 of wrist-pin 49 in contact with shoulders 51—51, whereby to confine said wrist-pin 49 and parts assembled thereon, namely plate 44, disks 39, 38, 37, sleeve 46, to a given position along ways or grooves 45—45, whereby said wrist-pin 49 may be functioned to act as a fulcrum for the longitudinal reciprocation of jaw 6, 40 which is actuated by disk 38 eccentrically controlled by lever handle 57 keyed at 58 to hub or sleeve 53, integral with disk 38. Jaw 5 is also adjusted with reference to nearness to jaw 6 by means of teeth 25 thereon and 45 teeth 24 of rack 11 which may be lowered from mesh with teeth 25 by pulling upward on lever handle 20. An object is held between jaws 5 and 6, whereupon the handle or lever 57 is moved from the position indicated in Fig. 5 to the position indicated in Fig. 2, the pull being a convenient one for a right handed operator, though the parts may be reversed for a left handed operator. In order to hold said handle 57 in this last 55 position whereby an object between jaws 5 and 6 will be firmly confined therebetween, or in other words in order to prevent handle 57 from slipping backward to its original position, the invention contemplates the employment of shoulders 42 and 43 of plate 44 which shoulders are rounded off at 58 and 59, so that shoulders 40 and 41, which are likewise rounded off at 60 and 61 will ride upon said shoulders 42 and 43 and thereby 60 effect a forcible contact of the said shoulders 65

with each other, which contact will in turn hold the handle 57 rigidly in any desired locking position. This locking means is effective for the reason that any wear may be taken up by tightening nut 48 upon wrist-pin 49.

Having thus described my invention, what I claim as new and desire to secure by Letters Patent is:

1. In a device of the character described, 75 the combination with a base of two jaws each adapted to be moved and fixed thereon, one of them having a toothed face on its lower surface, a bracket having teeth to engage with the said toothed face, the said bracket having portions depending below a fixed part of the base, a spring member acting to press the bracket upward from the base, means at one of the depending portions to adjust the bracket relatively to the 80 base and lever means at the other depending portion to raise or lower the bracket, by the coöperation of which means to put the teeth of the bracket into or out of contact with the toothed face of the jaw. 90

2. In a device of the character described, a base, a jaw mounted to be adjusted to a given position on the base, said jaw having its lower face provided with teeth, a bracket mounted on the base by means of a bolt or the like forming a pivotal support of the bracket on the base, the bracket being formed with an elongated slot for the bolt and a set screw being provided to position the bolt in the slot, lever members mounted 100 on the base and connected with the bracket to swing the bracket and spring means acting to keep the bracket with its teeth in contact with the toothed face of the jaw. 95

3. In a vise, the combination of a body, 105 jaws adjustably held with reference to each other, a relatively fixed adjustable jaw, a jaw adapted to approach and recede from the first named jaw, means for actuating said last named jaw, said means comprising a disk controlled by a handle, and means for holding the actuated jaw at any given position within the limits of its movement, said means comprising shoulders connected with said eccentric adapted to engage with corresponding shoulders on a plate adjustably held along a groove in said body. 110

4. In a vise, the combination of jaws held adjustably with reference to each other, and means for actuating one of said jaws to and from the other, said means comprising a metallic strap pivotally mounted to said jaw and to a disk, a handle mounted on a sleeve integral with said disk, whereby to rotate the same, and a secondary disk secured to 120 said disk and having shoulders adapted to engage with corresponding shoulders upon a plate, whereby to hold said disk at any point of its rotation, substantially as described. 125

5. In a vise, the combination of a body, 130

5 jaws having detachable faces, slidingly mounted upon said body, means for giving one of said jaws a rectilinear movement, said means comprising a disk to which said jaw is connected by a metallic strap, a hub eccentrically disposed upon said disk, a handle secured to said hub, whereby the movement of said handle turns said hub and disk and moves said jaw in a rectilinear manner, and 10 shoulders integral with said disk and adapted to engage with corresponding shoulders upon a plate adjustably held with reference to said disk, whereby said movable jaw may be held at any position within certain limits 15 of its movement.

6. In a vise, the combination of jaws slidingly mounted upon a body, means for giving one of said jaws a rectilinear movement, said means comprising a metallic strap pivotally connected to said jaw, a disk pivotally connected with said strap, a hub eccentrically mounted upon said disk, a handle to actuate said hub and disk, and means to hold said jaw at any given position within the 20 limits of its rectilinear movement, said means comprising shoulders integral with the under surface of said disk, said shoulders adapted to engage with corresponding shoulders integral with a plate adjustably held with reference to said disk, whereby the turning of said disk will cause the shoulders thereon to bind with the shoulders on 25 said plate, substantially as described.

7. In a device of the character described, 30 a base, the base having a longitudinal internal groove with overhanging edges, a wrist-pin having its head in said groove adapted to bear against said edges, a nut on the outer end of the wrist pin, members be-

35 tween the nut and the said head whereby, on the tightening of the nut, the wristpin is fixed in said groove, a jaw mounted on the base, a metallic strap connected to the jaw and having eccentric mounting on the wristpin, and means for rotating the eccentric 40 mounting of the strap whereby to move the 45 jaw.

8. In a vise, the combination with a base, of jaws movable to and from each other, means for fixing one jaw relative to the 50 base, said means consisting of a vertically movable toothed bracket and spring and lever means for placing the teeth in and out of contact with the jaw, the latter having teeth for such contact, and means for reciprocating and securing the other jaw, said means consisting of eccentrically mounted members engaging with the jaw and means connected with said members to hold the same at given points in their arc of movement. 55

9. In a device of the character described, the combination with a base, of a jaw with a toothed portion, a toothed member movable up or down but normally in contact with the 60 base and having a lever adapted to break such contact, a second jaw, a wrist-pin adjustable to a given fixed position on the base and eccentrically operative means connecting the wrist-pin and the jaw by the operation of which to reciprocate the jaw. 65

In testimony whereof I have hereunto affixed my signature in the presence of two witnesses.

JOHN B. DADE.
